UNITED STATES PATENT OFFICE.

BARTHOLOMEW O. WRIGHT, OF NEW ROCHELLE, NEW YORK.

DESIGN FOR AN UMBRELLA AND PARASOL TIP.

58,861.

Specification for Design.

Patented Aug. 30, 1921.

Application filed March 28, 1921. Serial No. 456,480. Term of patent 7 years.

To all whom it may concern:

Be it known that I, BARTHOLOMEW O. WRIGHT, a citizen of the United States, residing at New Rochelle, in the county of Westchester and State of New York, have invented a new, original, and ornamental Design for An Umbrella and Parasol Tip, of which the following is a specification, reference being had to the accompanying drawings, forming part thereof.

Fig. 2 is a side elevation viewed from a different angle; and

Fig. 3 is a plan view of the tip.

What I claim is:

The ornamental design for an umbrella and parasol tip as shown.

BARTHOLOMEW O. WRIGHT.
